UNITED STATES PATENT OFFICE.

OWEN L. DAUTRICK, OF DETROIT, MICHIGAN, ASSIGNOR TO THE DAUTRICK COMPANY, OF DETROIT, MICHIGAN, A CORPORATION OF MICHIGAN.

VERTICALLY-SLIDABLE INWARDLY-SWINGING WINDOW.

Application filed July 5, 1924. Serial No. 724,316.

To all whom it may concern:

Be it known that I, OWEN L. DAUTRICK, a citizen of the United States, residing at Detroit, county of Wayne, State of Michigan, have invented a certain new and useful Improvement in Vertically-Slidable Inwardly-Swinging Windows, and declare the following to be a full, clear, and exact description of the same, such as will enable others skilled in the art to which it pertains to make and use the same, reference being had to the accompanying drawings, which form a part of this specification.

My invention relates to an attachment for vertically slidable window sash whereby the sash may be swung inwardly for convenience in cleaning the outer face of the glass, as shown in the accompanying drawings and more particularly described in the following specification and claims.

It is well known that in large office or apartment buildings the problem of cleaning windows is one involving considerable annual expense due to the time required and the hazardous nature of the work.

The primary object, therefore, of the present invention is to provide an attachment for vertically movable window sash whereby the glass may be quickly and readily cleaned from the inside of the building, thereby greatly reducing the risk incurred by the party cleaning the windows and the time required to do the work.

A further object of the invention is to provide suitable metallic guides attached to the window casings adapted to co-act with elements carried upon the edge of the sash in order that the vertical movement of the sash may be facilitated and whereby the tendency to bind, common to ordinary sash in which two wood surfaces lie in contiguous relation is overcome.

A further object of the invention is to provide a close fitting overlapping construction thereby preventing the entry of drafts incident to the use of the ordinary wood sash and casing.

With the foregoing and other objects in view which will appear as the description proceeds the invention further resides in the combination and arrangement of parts and in the details of construction hereinafter described and claimed it being understood that changes may be made in the precise embodiment of the invention herein dis-

closed without departing from the spirit of the same.

In the drawings accompanying this specification:

Figure 1 is a fragmentary front elevation of a slidable channel member adapted for attachment to the usual sash cord connected with the lower detachable end of said slid- able channel member.

Figure 2 is a longitudinal sectional view taken on or about line 2—2 of Figure 1 showing the lower sash frame pivoted to the detachable end of the slidable channel member; the detachable end of the channel member being engaged by a latch carried by the body portion of said member.

Figure 3 is an enlarged view of an upper fragment of the channel member shown in Figure 1, engaged to the loop of a sash cord.

Figure 4 is a longitudinal sectional view through the slidable channel member, taken on or about line 4—4 of Figure 3,—con- nected with a sash cord.

Figure 5 is a cross-sectional view of the slidable channel member, and a co-acting guide or track plate secured to the window casing.—the window casing and sash frame being shown in dotted lines.

Figure 6 is a fragmentary perspective view of one of the slidable channel members with parts broken away showing a fragment of the sash frame pivoted to the lower de- attachable end of the channel member.

Figure 7 is a fragmentary perspective view with parts broken away and in section showing the lower sash swung into locked alignment with the slidable channel mem- ber that it may move vertically therewith.

Figure 8 is a fragmentary perspective view showing the lower sash swung into a room for cleaning, and the upper sash and channel frame,—to which the latter is piv- oted, lowered that it may be swung below the ends of the detachable slidable channel mem- bers of the lower sash,—indicated by the dotted lines, the full lines showing the upper sash and upper channel members raised in order that the upper sash may tilt over the detachable lower end portions of the chan- nel members supporting the lower sash, as it would appear when about to be laid upon the lower sash.

Referring now to the letters of reference placed upon the drawings:

A denotes a lower sash frame to the side members of which are secured plates A^a pivoted at A^{aa} to a relatively short channel member B carrying an upwardly projecting tongue B^b having a beveled end B^{bb} projecting into a relatively long vertically movable abutting channel member C, that the detachable channel member B may be held in locked relation with the latter by a spring latch D, fitted with a stud D^a adapted to enter an aperture b¹ provided in the tongue B^b riveted or otherwise secured to said lower detachable channel member B.

Projecting inwardly from the channel member C is a tongue C¹ adapted to receive a loop E attached to a weighted sash cord E¹.

Pivoted to the upper end of the channel member C is a spring actuated latch F adapted to engage a latch plate G secured to the side members of the sash frame near their upper ends to lock the sash in alignment with the vertically movable channel member. C² indicates a second tongue struck up from the body of the vertically movable channel member C and extending laterally to overlap the latch plate G to assist the latch F in maintaining the sash in proper alignment with the vertically movable channel members:—the side members of the sash frame being cut away to permit the tongue to pass beneath the latch plate as indicated at Figure 2.

H designates a guide rail secured to the side members of the window casing having flanged edges H^aH^a in spaced relation to the window casing to receive the inwardly directed edges C^a of the channel member C, forming a draft-tight joint with the flange H^a of the guide rail. The channel member C is also provided with a projecting flange C^b adapted to overlap the side member of the sash frame against which the sash is tightly held by the spring latches F.

Having now indicated the several parts by reference letters the construction and operation of the device will be readily understood:

When it is desired to swing the lower sash inwardly to clean the outside of the glass, the sash if raised is first lowered, the latches F pivoted to the slidable channel members are then released to permit the lower sash to swing inwardly on the pivots A^{aa}, projecting from the lower detachable channel members B, whereupon the outer face of the glass may be readily cleaned from the inside of the building.

To clean the upper sash the channel members CC of the lower sash are first disconnected from the lower detachable channel members BB by releasing the stud D^a carried by the spring latches D from the apertures b¹ in the tongues B^b. The channel members CC are then lifted under the action

of their respective counterpoised weights to the position indicated in Figure 8. The upper sash is then lowered until it touches the sill—as indicated in dotted lines in said figure. The sash is then released from the control of the spring latches F^x, that it (the sash) may swing below the vertically movable channel members CC, as indicated in dotted lines in the figure. The upper sash is then raised slightly to the position shown in full lines in order that it may swing over the lower detachable channel member B^b, whereupon it may be lowered so as to rest upon the lower sash that the outside of the glass may be readily cleaned.

After cleaning the windows the upper sash is swung back into its initial position in alignment with the upper movable channel members C^xC^x slidable on the guide rails H^x—the sash being secured in alignment by the spring latches F^x. It will be understood that the construction of the channel members and cooperating parts of the upper sash are substantially similar to those of the lower sash.

The channel members CC of the lower sash are then lowered into locking engagement with the detachable lower ends B. The lower sash is then swung back into its initial position in its channel members, to which it is again locked by the spring latches F. The sash frames are then in condition for operation as usual, or until the windows are to be cleaned again.

Having thus described my invention what I claim is:

1. In a device of the character described, a pair of vertically slidable members having detachable end portions located between the side rails of a sash frame and the window casing, means for linking the detachable end portions to the slidable members, guide rails secured to the window casing with edges spaced from the latter to receive the overlapping edges of the slidable members, sash weights connected with the slidable members, a sash frame pivoted to the detachable end portions of the slidable members, whereby the sash may be swung inwardly, and means for securing the sash frames in alignment with the slidable members, whereby the sash may be vertically raised or lowered.

2. In a device of the character described, a pair of vertically slidable members having detachable end portions located between the side rails of a sash frame and the window casing, means for linking the detachable end portions to the slidable members, guide rails secured to the window casing for receiving and guiding the slidable members, and a sash frame pivoted to the detachable end portions of the slidable members whereby the sash may be swung inwardly.

3. In a device of the character described, a pair of vertically slidable members located

- between the side rails of a sash frame, and the window casing and provided with detachable ends having a projecting tongue, spring actuated latches carried by the body
- 5 portion of the slidable members to engage the tongues of the detachable ends, whereby the ends are linked to the major portion of the slidable members, guide rails secured to the window casing for receiving and guid-
- 10 4. In a device of the character described, 15 a pair of vertically slidable members located between the side rails of a sash frame and the window casing and provided with detachable ends having a projecting tongue, spring actuated latches carried by the body
- 20 portion of the slidable members to engage the tongues of the detachable ends, whereby the ends are linked to the major portion of the slidable members, guide rails secured to the window casing having edges spaced
- 25 from the window casing to receive the overlapping edges of the slidable members, sash weights connected with the slidable members, a sash frame pivoted to the detachable ends of the slidable members and spring
- 30 actuated latches carried by the slidable members adapted to engage coacting elements secured to the sash to maintain the latter in vertical alignment with the slid- able members.
- 35 5. In a device of the character described,
- a pair of vertically slidable members located between the side rails of a sash frame and the window casing having detachable ends linked thereto, said slidable members having inwardly directed flanges adapted to overlap a pair of guide rails, a pair of guide rails secured to the window casing having their edges spaced from the latter to receive the overlapping inwardly directed flanges of the slidable members, a sash frame pivoted to the detachable ends of the slidable members, adapted to swing inwardly, a second pair of slidable members located between the side rails of an adjacent sash frame and the window casing, guide rails secured to the window casing having their edges spaced from the latter to receive the overlapping edges of the second pair of slidable members, a sash frame pivoted to said second pair of slidable members adapted to swing inwardly upon the first named sash frame upon detaching the latter from its slidable members, sash weights connected with the respective slidable members and means carried by the slidable members including coacting elements secured to the respective sashes adapted to maintain the sashes in alignment with the slidable members, where- by they may be vertically raised or lowered.
- In testimony whereof, I sign this specifica-
tion in the presence of two witnesses.
- OWEN L. DAUTRICK.
